TAPER FEEDING HAIR CLIPPER COMB

Joseph Cromonic, Brooklyn, N. Y.

Application September 27, 1937, Serial No. 165,865

4 Claims. (Cl. 30—201)

This invention relates to new and useful improvements in a taper feeding hair clipper comb.

The invention has for an object the construction of a feeder for a hair clipper which is adapted to so feed the hair clipper that it is capable of cutting one's hair in a smart and neat taper.

More specifically, the invention proposes the provision of a spacer comb in conjunction with the comb plates of the cutter, and arranged in a manner so that the distance of the spacer comb may be readily varied from the comb plates of the cutter to control the taper of cutting of one's hair.

Still further the invention contemplates the provision of a handle which may be conveniently moved by one's finger and which is capable of extending the spacer comb to various amounts in direct relation to which the handle is moved.

Still further the invention proposes to characterize the spacer comb by the fact that it is provided with rack elements engaging slots in the stationary comb of the hair clipper, the provision of a shaft with gear segments meshing with racks, and the arrangement of mounting the handle on the shaft by which the gear segments and racks, and so the spacer comb, may be controlled.

Still further the invention contemplates associating a spring in a specific manner with turnable shaft so that normally the spacer comb tends to maintain a retracted position.

Still further the invention proposes several modified forms by which the spacer comb may be extended or retracted to various degrees as required.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a hair clipper with a spacer comb associated therewith according to this invention.

Fig. 2 is a bottom view of Fig. 1.

Fig. 3 is a perspective view of the spacer comb and its operating mechanism per se.

Fig. 4 is an enlarged fragmentary detailed view of a portion of Fig. 3.

Fig. 5 is a fragmentary plan view of Fig. 1 looking in the direction of the line 5—5 thereof.

Fig. 6 is an enlarged detailed view of a portion of Fig. 1, namely the left hand end.

taken on the line 7—7 of Fig. 2.

Fig. 8 is a sectional view taken on the line 8—8 of Fig. 6.

Fig. 9 is an enlarged detailed elevational view looking in the direction of the line 9—9 of Fig. 8.

Fig. 10 is a side elevational view similar to Fig. 6 but illustrating a modification.

Fig. 11 is a fragmentary perspective view of the spacer comb used in Fig. 10.

Fig. 12 is another view similar to Fig. 6 but showing another modification of the invention.

The taper feeding hair clipper, according to this invention, makes use of a hair clipper having a movable comb plate 10 cooperative with a stationary comb plate 11 on the rear end portion of which there is mounted a cover plate 12, a stationary handle 13, and a movable handle 14 for moving said comb plate 10. The movable handle 14 is pivotally supported by a pintle screw 15 and has a projecting finger 14^a which engages an element 10^a on the movable comb plate by which the comb plate may be moved. A spring 16 is associated with the movable handle 14 in a manner so as to normally extend the handle 14 so that the handles 13 and 14 may be moved together to cause the movable plate to move. Further details of the construction of the hair clipper will not be given in this specification since they form no part of the invention and are of standard construction generally known.

In combination with the hair clipper specified, there is a spacer comb 18 which engages over the said comb plates 10 and 11 and which is slidably mounted on the stationary comb 11 by reason of rack elements 19 extending from the side edges of the spacer comb and slidably engaging in slots 20 formed in the end portions of the stationary comb 11. These slots 20 are arranged at an inclination to correspond with the inclination of the rack elements 19 (see particularly Fig. 1) whereby when the rack elements 19 are extended the spacer comb will be correspondingly moved, as for example shown by the dot and dash lines 18' in Fig. 1.

A shaft 21 is turnably mounted through the cover plate 12. Gear segments 22 are mounted on the shaft 21 and engage the teeth of the rack elements 19. The handle 23 is mounted on the shaft 21 by which it may be manually turned by one's finger for moving the same.

The rack elements 19 and the corresponding parts may be of any suitable size to insure a smooth operating action.

The spacer comb 18 comprises a plate element 55

18^a from which a plurality of teeth 18^b project. These teeth are bent so as to engage over the teeth of the comb plates 10 and 11. The plate portion 18^a is adapted to extend beneath the bottom face of the stationary comb 11. The spacer comb 18 is so constructed that it will hold the hair clipper at different distances from one's scalp depending upon the extent to which it is extended and so control the tapering of one's hair.

10 The shaft 21 is formed from two sections. There is a section 21^a and a section 21^b. These sections are in end alignment with each other and have their adjacent ends formed with overlapping parts (see Fig. 9). These parts are

15 secured together with a pin 25. This pin 25 also secures a radially extending clip element 26 upon the shaft 21. A spring 27 connects with the outer end of this clip element and extends rearwards through the hollow of the cover plate 12 and connects with a stationary pin 28. The arrangement is such that the spring 27 acts to normally hold the shaft 21 in a turned position, in which position the gear segments 22 hold the spacer comb fully retracted. The handle 23 may

20 be depressed, turned clockwise in relation to the showing in Fig. 1, to correspondingly turn the gear segments and so extend the spacer comb.

At the ends, each of the gear segments 22 are provided with projecting finger portions 22^a 30 which are adapted to strike against the free ends of the racks 19 and eject the racks from the slots 20 when the gear segments 22 are turned to their fullest extent clockwise. Thus it is possible to easily remove the spacer comb. This is done merely by pressing the handle 23 downwards to its fullest extent. To re-engage the spacer comb in position the handle 23 must be pressed down to its fullest extent and then the spacer comb shoved upwards until the free ends of the racks 40 19 strike the fingers 22^a. Then as the handle 23 is permitted to move upwards the gear segments 22 will draw in the racks 19, and so move inwards the spacer comb.

A means is provided for limiting the position 45 to which the handle 23 may move anti-clockwise and so control the amount to which one's hair may be clipped. This means comprises a lug 30 projecting from the side of the cover plate 12 and supporting an adjustment screw 31 which is threadedly engaged therein. This adjustment screw is adapted to have its lower end strike the handle 23 and form a stop for the handle. It is possible to turn the screw 31 to cause it to move upwards and downwards and so change the adjustment.

In Figs. 10 and 11 a modified form of the invention has been disclosed which distinguishes from the prior form in the construction and operation of the spacer comb. According to this form of the 60 invention a lever 33 is pivotally attached by a pintle 34 upon each end of the stationary comb 11. The top end of each lever 33 is provided with a pivotally supported arm 34 which extends forwards and engages into a socket 35 formed upon 65 the top of the spacer comb 38. The lower end of each lever 36 may be manually depressed for controlling its pivoting and so the extension of the spacer comb 38. Each end of the lever 33 extends downwards and is adapted to be rested 70 against one's hair and scalp so that by changing the inclination of the clipper relative to one's head it is possible to cause the lever 33 to pivot and so automatically control the spacer comb 38 without the necessity of any direct control 75 thereof.

A direct control is provided for the spacer comb 38, and comprises a link 39 pivotally connected with one of the levers 33, and in turn pivotally connecting with a handle 40. This handle 40 is pivotally supported by a pin 41 to the stationary comb 11. A spring 42 is connected with one of the levers 33 to normally urge the lever into a position in which the spacer comb 38 is retracted. The arrangement is such that the handle 40 may be manually pressed forwards with one's finger 10 to pivot one of the levers 33, and so control the extension of the spacer comb.

In Fig. 12 a still further embodiment of the invention has been disclosed in which a link 44 is pivotally mounted by a pin 45 on each side of the 15 cover plate 12. On the extended end of each link 44 there is a holding arm 46. These holding arms are adapted to engage in socket portions 47 formed on the top portions of the spacer comb 48. The connection between the holding arms 20 and the sockets 47 is frictional. The arrangement is such that the spacer comb 48 may be manually pulled off from the holding arms 46. Then the holding arms and links 44 may be pivoted to the inoperative positions indicated by 25 the dot and dash lines designated 44' and 46'.

It is required that an operator place his finger against the side of at least one of the holding arms 46 and manually control the extension and retraction of the spacer comb 48. 30

While I have illustrated and described the preferred embodiments of my invention, it is to be understood that I do not limit myself to the precise constructions herein disclosed and the right 35 is reserved to all changes and modifications coming within the scope of the invention as defined in the appended claims.

Having thus described my invention, what I claim as new, and desire to secure by United 40 States Letters Patent is:

1. In combination with a hair clipper having a movable comb plate cooperative with a stationary comb plate on the rear of which is mounted a cover plate, a stationary handle and a movable 45 handle for moving said movable comb plate, a spacer comb engaging over said combs and slidably mounted on said stationary comb plate by rack elements thereof engaging slots in said stationary comb, a shaft turnably mounted on said cover plate, gear segments mounted on said shaft and engaging said rack elements, and a handle on said shaft by which it may be manually turned by one's finger for moving the same, said shaft being formed of sections having overlapping 50 portions, and a pin for holding said sections together, a lug mounted upon said shaft and held by said pin, and resilient means connected with said lug and a stationary part on said hair clipper for tending to turn said shaft in one 55 direction.

2. In combination with a hair clipper having a movable comb plate cooperative with a stationary comb plate on the rear of which is mounted a cover plate, a stationary handle and a movable 65 handle for moving said movable comb plate, a spacer comb engaging over said combs and slidably mounted on said stationary comb plate by rack elements thereof engaging slots in said stationary comb, a shaft turnably mounted on said cover plate, gear segments mounted on said shaft and engaging said rack elements, and a handle on said shaft by which it may be manually turned by one's finger for moving the same, each of said 70 gear segments being provided with projecting 75

fingers adapted to engage the ends of said rack elements in turned positions thereof.

3. In combination with a hair clipper having a movable comb plate cooperative with a stationary comb plate, means for moving said movable comb plate to clip hair which engages between the teeth of said comb plates, a spacer comb plate upon which said comb plates are mounted, teeth formed on the front end of said spacer comb plate and being bent into an acute angle to engage over the front edges of said comb plate to simultaneously hold said hair clipper in a slopped forward position and to continually feed hair to said comb plates while said hair clipper is being advanced over the surface to be clipped.

4. In combination with a hair clipper having a movable comb plate cooperative with a stationary

comb plate, means for moving said movable comb plate to clip hair which engages between the teeth of said comb plates, a spacer comb plate upon which said comb plates are mounted, teeth formed on the front end of said spacer comb plate and being bent into an acute angle to engage over the front edges of said comb plate to simultaneously hold said hair clipper in a slopped forward position and to continually feed hair to said comb plates while said hair clipper is being advanced over the surface to be clipped.
